UNITED STATES PATENT OFFICE

2,577,034

DOORWAY GATE

John H. Quinlan, St. Paul, Minn.

Application April 16, 1949, Serial No. 87,861

3 Claims. (Cl. 160—217)

1

This invention relates to a gate or a guard structure for confining small children in a room or other portion of a dwelling or enclosure and particularly to a gate adapted to be fastened in a doorway or other passage such as a stairway where there are oppositely disposed walls or frame members suitably spaced for engagement with the gate members.

It is an object of my invention to provide an inexpensive gate adapted to be securely held between opposing wall or jamb members solely by friction and without the use of hardware of any kind for fastening the device to the woodwork or walls of the dwelling.

A further object is to provide a device of the class described which may be quickly and easily secured in its operative position in a doorway and as quickly removed and folded to compact form when not in use.

A particular object is to provide a gate of the class described composed of a pair of similar rigid sections hingedly connected together to oscillate one relative to the other about a vertical axis, the sections being adapted to be forcibly aligned by moderate pressure applied to the central portion of the structure whereby the pressure required to frictionally and securely engage vertically disposed members defining a doorway or other passageway is applied by toggle-like action of the gate sections.

The invention also includes certain novel details of construction which will be more fully pointed out in the following specification and claims.

Referring to the accompanying drawing which illustrates, by way of example and not for the purpose of limitation, a preferred embodiment of my invention:

Figure 1 is a plan view of my improved gate in operative relation to a door frame of common type, the vertical frame members being shown in horizontal section;

Fig. 2 is a front elevational view of the gate; Fig. 3 is an end view of the same, and

Fig. 4 is a fragmentary vertical section taken on the line 4—4 of Fig. 2.

Referring to the drawing, my improved gate is composed of a pair of similar sections, indicated generally by the numerals 5 and 6 respectively, hingedly connected together by hinges 7 so that the sections may be folded to lie flat one on the other and extended in a common substantially vertical plane when in use, as indicated in full lines in Fig. 1. On the side opposite to the hinges 7, I provide a pair of latches each comprising a rigid hook member 8 pivotally connected by a

2

pin 9 to the section 5 and having a free end formed with a notch adapted to receive a latch pin 10 projecting from the gate section 6. A pair of resilient cushion members 11 are mounted on the outer ends respectively of the gate sections 5 and 6 for engagement with the vertically extending jamb members 12 of the door frame or other passageway in which the gate is to be used (Fig. 1). The cushion members 11 are preferably

rubber suction cups adapted to adhere to the jamb member surfaces without damaging them.

Each gate section comprises an upper rail 13, bottom rail 14 and parallel extensible rail members 15 and 16 which are slidable along the rails 13 to adapt the gate to fit doorways of various widths. Each rail member 15 is rigidly connected in spaced parallel relation to a member 16 by a series of vertically extending bars 17 suitably spaced apart one from another to prevent the escape of a small

child between them. Wing bolts 18 extend vertically through openings in the rail members 15 and 16 and also through elongated slots 19 formed in the rails 13 and 14 whereby these extensible rail members may be secured in adjusted positions relative to the rails 15 and 16. As best shown in Fig. 4, each of the rail members 15 and 16 is guided in a channel shaped groove formed in one of the rails 13 or 14. In addition to the bars 17, the central portion of the gate is provided with a pair of spaced bars 20 which rigidly connect the

upper rails 13 to the lower rails 14.

To adjust the width of the gate to fit a doorway of any of the common widths, the nuts on the wing bolts 18 are loosened and the gate sections 5 and 6 are placed across the selected doorway at an obtuse angle, one relative to the other, e. g. as indicated in broken lines in Fig. 1, and then the extensible rail members 15 and 16 are moved outward or extended until the cushion members 11 make light contact with the opposed jamb surfaces of the members 12. Thereupon the wing nuts are tightened and the gate sections are forcibly aligned by pressure applied either to the central bars 20 or directly to the central portions of the rails 13 and/or 14.

Finally the latch members 8 are engaged with the pins 10 to retain the gate in the operative position in which it is securely held by frictional engagement of the cushion members 11 with the jamb members 12 at opposite ends of the gate. To withdraw or open the gate relative to the passageway, the latch members 8 are merely disengaged from the pins 10 and the central portion of the gate drawn outward. When not in use, the sections 5 and 6 may be folded one upon another.

The cushion members 11 are preferably constructed from suitably soft rubber or similar composition which is compressible and of such character as to avoid marring the woodwork or walls with which they are engaged.

It will be evident that my improved gate is unusually simple and inexpensive in construction and is readily movable from one doorway to another for use wherever needed. No hardware is required for connecting the gate members to the woodwork or walls and a minimum of skill is required to install and manipulate the gate to and from closed position.

Having described my invention, what I claim as new and desire to protect by Letters Patent is:

1. In a gate for use in a doorway having oppositely disposed jamb members, a pair of gate sections hingedly connected together to extend substantially in a common vertical plane between said jamb members, each of said sections comprising upper and lower main rail members and extension rail members slidably along and extensible laterally outward from the ends of said main rail to close doorways of various widths, bars rigidly and directly connecting the main rail members of each section together, a series of spaced vertically extending bars rigidly connecting the extension rail members of each gate section together, a compressible cushion member carried by the outer end of each of said extension rail members for engagement with said jamb members and latch means for securing said gate sections in a common plane between the jamb members of said doorway.

2. In a gate for use in a doorway having oppositely disposed jamb members, a pair of gate sections hingedly connected together to fold one upon the other about a vertical axis, each of said sections comprising upper and lower main rail members of channel shape in cross section and upper and lower extension rail members slidably fitting in the channels defined by the main rail members, said extension rail members being extensible from the outer ends of the main rail members to close doorways of various widths, a vertically extending bar rigidly and directly con-

necting the main upper rail member to the main lower rail member of each gate section to retain said rail members in fixed vertically spaced relation, a series of bars connecting the upper extension rail member to the lower extension rail member of each section together, means for rigidly securing each of said extension rail members to a main rail member in selected positions thereon, and latch means for securing said gate sections in a common plane between the jamb members of the doorway.

3. In a gate for use in a doorway having oppositely disposed jamb members, a pair of gate sections hingedly connected together to fold one upon the other about a vertical axis, each of said sections comprising upper and lower main rail members of channel shape in cross section and upper and lower extension rail members slidably fitting in the channels defined by the main rail members, said extension rail members being extensible from the outer ends of the several main rail members to close doorways of various widths, means rigidly and directly connecting the main upper rail member to the main lower rail member of each gate section, a series of bars rigidly connecting the upper extension rail member to the lower extension rail member of each section together, screw threaded means adapted to clamp the several extension rail members in the channels of the main rail members in selected positions thereon, and latch means for securing said gate sections in a common plane between the jamb members of the doorway.
